UNITED STATES PATENT OFFICE.

ELLA A. KENDALL, OF PHILADELPHIA, PENNSYLVANIA.

WATERPROOF HAT-PROTECTOR.

No. 902,969.

Specification of Letters Patent.

Patented Nov. 3, 1908.

Application filed May 11, 1908. Serial No. 432,010.

To all whom it may concern:

Be it known that I, ELLA A. KENDALL, a citizen of the United States, residing in Philadelphia, Pennsylvania, have invented 5 certain Improvements in Waterproof Hat-Protectors, of which the following is a specification.

One object of my invention is to provide a cover of such a nature and construction as 10 to be capable of application to hats of widely different forms and sizes, for the purpose of protecting them from moisture, dust or wind.

It is further desired to provide a water- 15 proof cover, which, in addition to being light and easily carried, may be quickly and conveniently applied or removed from a hat, as well as easily adjusted to fit hats of widely varying sizes. I also desire to pro- 20 vide a hat cover with improved means for holding it in position upon a hat.

These objects and other advantageous ends I secure as hereinafter set forth, reference being had to the accompanying drawings, in 25 which—

Figure 1, is a perspective view illustrating 30 my improved cover applied to a hat; Fig. 2, is a perspective view illustrating the cover when removed; Fig. 3, is a vertical section of a hat showing my improved cover applied thereto; Fig. 4, is an inverted plan of the cover; and Fig. 5, is a perspective view of a form of hook preferably em- 35 ployed as part of my invention for holding the cover in place upon a hat.

In the above drawings, A represents my improved cover, which in the present instance consists of two rectangular pieces of fabric having an elongated form and united 40 to each other along one edge. The cover, however, is given an approximately circular or elliptical form by reason of the fact that the material is plaited at the center, as shown in Fig. 4, and over this plaited portion is sewed or cemented an elongated or other suitably shaped piece a.

It will be understood that while I prefer- 50 ably construct my hat cover of two pieces, as above noted, it may, if desired be made of one or any number of pieces of material, suitably connected and plaited or otherwise arranged to give it the desired shape.

As shown in Fig. 4, I provide one or more drawing strings b, extending from the central piece a to the front edge of the cover, whereby said edge may be drawn toward the

center to give the front portion a series of folds or gathers, as illustrated at b' in Figs. 1 and 2, so as to make the cover capable of fitting a small sized hat while allowing it to 60 be adjusted to fit larger hats or hats having trimmings of varying sizes.

The edge of the cover is turned over and faced, and has under the facing a tape to which are fixed at suitable intervals a series 65 of hooks c whose bills extend substantially parallel to the under face of said cover. While said hooks may be of any desired form or construction, they are preferably made of flat pieces of sheet metal, as shown 70 in Fig. 5, provided with a series of small projections or tongues c' and having a bill c² formed integral with their body portions. These hooks are preferably attached to a suitable length of tape through which the 75 projections c are passed and over which they are turned. Such tape is then placed around the edge of the cover preferably under the facing, as illustrated, while the bills of the hooks project inwardly from the under side 80 of the cover, the whole being so arranged that the hooks are some distance away from said edge.

In applying my cover to a hat of the ordinary size in which the trimming occupies 85 but relatively little space, the drawing strings b can be so adjusted as to gather the front portion of said cover, as illustrated in Figs. 1 to 4, inclusive, and the hooks are made to engage the rim of the hat. The 90 cover, is, therefore, firmly held in position and extends beyond the rim of the hat so as to effectually shed any water without permitting it to wet the hat.

Should it be desired to apply the cover to 95 a hat having large or extended trimming the drawing string b is released, thereby permitting the front portion of the cover to be extended to its utmost or to any amount de- sired.

The material employed for the cover is preferably a fabric whose surface has been treated with rubber to render it waterproof, and, as is obvious, the fabric and hooks may be of any desired colors; its general style and arrangement of parts being susceptible of wide variation without departing from my 105 invention.

When made of light material the cover occupies but relatively little space and has 110 but a small weight and when applied to a hat, as described, the holding devices are

amply sufficient to retain it in position to effectually protect the hat even in a high wind.

I claim:

- 5 1. A hat cover consisting of a body of waterproof material of a generally circular form having means whereby it is maintained permanently gathered at its central portion, and having along its edge a series of 10 retaining devices for detachably holding it to a hat.
- 15 2. A hat cover consisting of a piece of waterproof material having means at its edge whereby it may be detachably secured 15 to a hat, and provided with means whereby it may be gathered in a line substantially radial to its center to adjust its size.
- 20 3. A cover consisting of a body of waterproof material having means at its edges for detachably securing it to a hat, and provided with a drawing string or strings extending radially from one edge toward its center whereby it may be gathered to vary its size at will.

4. A cover consisting of a body of water 25 proof material plaited at its central portion, a piece of material extending over and cemented to said plaited portion, and a series of inwardly extending hooks placed on the under side of the body, so as to be capable 30 of engagement with the rim of a hat.

5. A cover consisting of a body of water 35 proof material constructed to fit over a hat, and provided with means whereby it is detachably maintained in position, said means 40 consisting of a tape attached to and extending around the edge of the cover, with a series of hooks fixed to said tape so that their bills extend inwardly from the edge of the cover, said hooks being placed some distance away from said edge.

In testimony whereof, I have signed my name to this specification, in the presence of two subscribing witnesses.

ELLA A. KENDALL.
